(57) **CLAIM**

The ornamental design for a refilling needle for inkjet cartridge, as shown and described.

DESCRIPTION

FIG. 1 is a perspective view of refilling needle for inkjet cartridge showing my new design;

FIG. 2 is a front elevational view;

FIG. 3 is a rear elevational view;

FIG. 4 is a top plan view;

FIG. 5 is a bottom plan view;

FIG. 6 is a left side elevational view;

FIG. 7 is a right side elevational view;

FIG. 8 is an elevational view; and

FIG. 9 is another elevational view.

The broken lines showing an ink cartridge in FIGS. 8-9 are for illustrative purposes only and form no part of the claim design.
